CONTROLLER FOR PNEUMATIC THREAD
REMOVERSClarence R. Kronoff, Worcester, Mass., assignor
to Crompton & Knowles Loom Works, Worcester,
Mass., a corporation of Massachusetts

Application March 25, 1950, Serial No. 151,875

10 Claims. (Cl. 139—256)

1

This invention relates to improvements in thread remover mechanisms for the outgoing thread in weft replenishing looms and it is the general object of the invention to prevent the thread remover from being moved to thread pick-up position if a bobbin transfer operation occurs while a shuttle is misplaced.

It has been proposed heretofore to utilize a pneumatic thread remover between the reserve bobbin magazine and the cloth normally in inactive or thread non-pick-up position but moved to active or thread pick-up position by the transerrer arm incident to a weft replenishing operation of the loom. It is customary to employ so-called shuttle position detectors or feelers which operate to prevent or revoke a previously called bobbin transfer if the shuttle is misplaced, thereby preventing descent of the transerrer arm. In some instances, however, the shuttle position detector will fail to prevent movement of the transerrer arm if the shuttle is only slightly misplaced and if under these conditions the shuttle is in the path of the thread remover there is likely to be breakage of either the remover or the shuttle.

It is an important object of the present invention to provide detachable operating mechanism between the transerrer arm and the thread remover under control of the shuttle position detector and operated by the latter if the shuttle is misplaced to prevent operative connection between the remover and transerrer arm should the latter have an operating stroke due to failure of the shuttle position detector to revoke transfer.

More particularly, it is an object of the invention to provide bobbin transerrer and thread remover members on one of which is mounted a force transmitter or actuator element to cooperate with an actuated element on the other member, and place one or the other of the elements under control of the shuttle position detector to be moved by the latter to inoperative position in the event a shuttle is misplaced to prevent movement of the thread remover member by the transerrer member.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a side elevation of a weft replenishing mechanism as viewed from the center of the loom having the present invention applied thereto, the lay being shown in cross section,

2

Fig. 2 is an enlarged view of the lower part of Fig. 1 showing the mechanism in one position in full lines and in a different position in dotted lines,

5 Fig. 3 is a vertical section on line 3—3, Fig. 2,
Fig. 4 is an enlarged vertical section on line 4—4, Fig. 3,

Fig. 5 is a plan view of part of the mechanism looking in the direction of arrow 5, Fig. 2,

10 Fig. 6 is an enlarged vertical section on line 6—6, Fig. 5, and

Figs. 7 and 8 are diagrammatic views showing the invention in different positions.

Referring particularly to Fig. 1, the loom frame 1 supports a multicolor reserve bobbin magazine M which includes in its construction a transerrer arm 2 pivoted on a stud 3 fixed with respect to the stationary magazine foot 4. The transerrer arm is provided with a transerrer 15 latch 5 for cooperation with a bunter 6 on the lay L. The magazine includes a top shaft 7 operatively connected by rod 8 to the latch 5 and by a second or resetting rod 9 to a carrier 10 pivoted on a stud 11 fixed with respect to the magazine M. Secured to and extending forwardly from the carrier 10 is a shuttle position detector or feeler 12 which is normally in raised position above the lay and the path of shuttle S.

When a weft replenishing operation is called 30 shaft 7 rocks to depress both of the rods 8 and 9, the former rod lifting latch 5 into the path of bunter 6 to cause a rocking motion of the transerrer arm 2 in a counterclockwise direction around stud 3 as viewed in Fig. 1 as the lay 35 approaches its front center position, and rod 9 swinging the carrier 10 in a clockwise direction around stud 11 to lower the shuttle position detector or feeler 12 to the detecting position shown for instance in dotted lines in Fig. 2.

40 The thread remover member designated generally at R includes a carrier 15 mounted for angular motion on the stud 3. A flat spring 16 held in place by a nut 17 on stud 3 forces the carrier frictionally against the hub 18 for the 45 stud 3 and acts to hold the remover member R in any position to which it may be moved.

An elongated member or rod 20 is slidably mounted on the carrier 15 and has a thread remover tube 21 secured to the rear end thereof provided 50 with a thread pick-up hook 22 extending under a thread intake mouth 23. The upper end of tube 21 is connected by a hose 24 to a thread collector 25 the upper end of which is connected by pipe 26 to any approved source of subatmospheric pressures.

55 A spring 27 surrounding part of rod 20 is inter-

posed between the carrier 15 and a thread baffle plate 23 fastened to the rear end of the rod 20 and also to the tube 21. Carrier 15 has a lateral wing 29 overhanging a vertically movable rod 39 which is normally in down position during a bobbin transferring operation but rises at a later point in the loom cycle to return the carrier 15 and remover R to their normal positions.

In the operation of the weft replenishing features of the loom the latch 5 and shuttle position detector 12 will be moved to their operating positions while the lay L is in a rearward position and if the shuttle is properly boxed it will not engage the feeler 12 and a bobbin transferring operation can proceed in usual manner. Shuttle box back 31 will thereafter lift feeler 12 as the lay approaches front center to reset shaft 7. If, however, the shuttle projects out of its shuttle box as the lay advances it will engage the under side of the shuttle feeler 12 and lift the latter, thereby raising rod 9 and rocking shaft 7 back to its normal position while the lay is still some distance behind front center. Under this last condition the latch 5 will ordinarily drop out of the path of the bunter, but if the latch is slow in falling it will be engaged by the bunter and the transerrer arm will descend to place a reserve bobbin drawn from the magazine into the shuttle S despite the fact that the shuttle feeler attempted to revoke transfer.

The matter thus far described is of common construction and except as noted hereinafter operates in usual manner.

In the past the transerrer arm has been provided with a fixed stud overhanging a part of the carrier 15 so that the latter was necessarily pushed down to move the thread remover to thread pick-up position whenever the transerrer arm performed a bobbin changing operation. In these prior constructions some breakage of the thread remover has resulted due to the fact that the shuttle was misplaced far enough to be in the path of the remover but not far enough to enable the shuttle position feeler 12 to revoke or prevent bobbin transfer. It is the general purpose of the present invention to provide a form of operating connection between the transerrer arm 2 and the remover R under control of the shuttle feeler 12 operating in such manner that a slight motion of the feeler 12 by a misplaced shuttle will be sufficient to prevent movement of the remover by the transerrer arm.

In carrying the invention into effect the magazine is provided with a fixed support 35 somewhat similar to stands used heretofore but for a different purpose. A stud 36 is secured to support 35 by set screw 37. Rockable on stud 36 is a lever 38 which in the present instance has a rearwardly extending arm 39 attached to a rod 40 the lower end of which is pivotally connected as at 41 to an arm 42 of carrier 10.

Lever 38 has a forward arm 43 for cooperation with an actuator element designated generally at 44 and mounted for pivotal movement on the transerrer arm 2. As shown in Fig. 3 the transerrer arm has a stud 45 secured thereto as at 46 and is provided with the reduced end 47 on which is pivotally mounted the hub 48 of actuator element 44. A torsion spring 49 surrounds part of the stud 45 and has one end 50 thereof held by a collar 51 fixed in angularly adjusted position on the stud and has the other end 52 thereof connected to the actuator element 44.

The actuator element has a finger or arm 55

for cooperation with lever arm 43 and is normally held against the latter by the spring 49. The latch member 44 is also provided with a dagger, dog, or pawl 56 held adjustable on the latch by a nut 57. Stud 45 has extending therethrough a stop pin 58 received by pockets 59 and 60 in the hub 48 to limit angular movement of the actuator with respect to the stud. The carrier 15 has secured thereto a finger or actuated element 61 formed with a rearwardly bent hooked lower end 62, see Fig. 2.

In operation the parts will normally be in the position shown in full lines in Fig. 2 with the shuttle feeler 12 raised and with lever arm 43 pressing down against finger or arm 55 so that the actuator 44 is moved angularly around stud 45 to its extreme right hand inoperative position as viewed in Fig. 2 so that dog 56 will be out of register with the finger 61. When the magazine is set for transfer, as already explained, the shuttle feeler 12 will move from the full line position to the dotted line position shown in Fig. 2 and in doing so will exert a downward force on rod 40 to rock lever 38 in a counter-clockwise direction around stud 45 as viewed in Fig. 2. This permits spring 49 to rock the actuator element from the full line position to the dotted line position shown in Fig. 2 in which the dog 56 will overhang and be cooperatively related to the finger 61. If the ensuing transfer is normal the remover R will be moved down to its thread pick-up position indicated in dash lines in Fig. 2 as the transerrer arm descends by cooperation of the actuator element 44 and the actuated element 61.

The transerrer arm will reach its lowest position as the lay reaches front center and will move the remover R until its transferring stroke is completed. As the lay approaches front center, however, the back 31 of the shuttle box will restore the shuttle feeler 12 to its normal position and lever 38 will return to its normal full line position shown in Fig. 2. Resetting of the magazine is ordinarily completed when the lay reaches front center, having started while the lay is still a short distance rearward of front center as it moves forwardly. The lever arm 43 will therefore return to the full line normal position shown in Fig. 2, but at this time the transerrer is down with the arm 55 of the actuator 44 spaced below lever arm 43, and the dog 56 is caught in the hook 62.

As soon as the lay starts to move backwardly subsequent to transfer the transerrer arm will rise, but pin 58 will prevent the latch from having any further angular motion due to spring 49 with respect to stud 45 in a counter-clockwise direction, Fig. 2, as the dog 56 leaves the hook 62. As the transerrer arm approaches its normal raised position the previously reset lever 43 will engage finger 55 and rock the actuator 44 in a clockwise direction, Fig. 2, back to its normal position. The operation of lever 38 and actuator 44 just described is for a normal bobbin transfer with the shuttle properly boxed.

Should the shuttle be misplaced when the magazine is set for transfer and project under remover R it will strike the shuttle feeler 12 and move it from the full line position to the dotted line position of Fig. 7, thereby rocking lever 38 to exert a positive force on element 44 moving it from its operative position shown in full lines in Fig. 7 to its inoperative position out of register with element 61. If the shuttle is widely misplaced the movement of shuttle feeler 12 may oc-

cur early enough to cause revocation of transfer by dropping of latch 5 and both the transerrer arm and remover will remain up in their normal positions. Should the shuttle be only slightly misplaced, or should revocation fail even with a widely misplaced shuttle, the transerrer arm will move down as indicated in dotted lines in Fig. 8, but the shuttle feeler 12 will previously have rocked element 44 to its inoperative position and the remover R will remain up as element 44 descends as indicated in dotted lines, Fig. 8, without engaging element 61. Thereafter the actuator will be free to turn in response to spring 49 after finger 55 moves downwardly out of engagement with lever arm 43, but by this time the dog will be below and cannot engage the finger 61. As the transerrer arm thereafter returns to normal raised position arm 55 will engage lever arm 43, by this time in full line position, Fig. 2, and actuator 44 will be rocked back to its normal position. From this it will be apparent that a minimum amount of movement of shuttle feeler 12 by a slightly misplaced shuttle will suffice to prevent movement of the remover R on the transerrer arm.

From the foregoing it will be seen that the invention sets forth means by which the pneumatic thread remover will normally be moved to thread pick-up position by the transerrer arm, but if the shuttle is misplaced the actuator and actuated element will be in non-cooperative relative position to prevent descent of the remover R by the transerrer 2 should the latter have an operation due to failure of the revoking operation. Each time the magazine is set for a weft replenishing operation the dog 56 will move into a position over the finger or hook 62 and normal movement of the remover by the transerrer arm will occur if the shuttle is properly placed, but if the shuttle is slightly misplaced rocking of lever 38 will positively turn actuator 44 in such a direction as to move the dog 56 out of register with the hook 62. While the invention is of more particular use in connection with shuttles which are only slightly misplaced it will be understood that it also operates satisfactorily should the shuttle be more widely misplaced.

Having thus described the invention it will be seen that changes and modifications of the foregoing specific disclosure may be made without departing from the spirit and scope of the invention.

What is claimed as new is:

1. In a weft replenishing loom, a bobbin transerrer member having an operating stroke incident to a weft replenishing operation of the loom, a thread remover member normally in thread non-pick-up position but movable to thread pick-up position, means including two cooperative relatively movable elements, one on each of said members, in cooperative position incident to a replenishing operation of the loom to transmit force from the transerrer member to the remover member upon an operative stroke of the transerrer member to move the remover member to thread pick-up position, a shuttle position detector in detecting position incident to a weft replenishing operation, and means controlled by the shuttle position detector effecting relative movement of said elements to non-cooperative position upon movement of the shuttle position detector away from the detecting position thereof by a misplaced shuttle to prevent the transerrer member from moving the remover member to pick-up position.

2. In a weft replenishing loom, an operating member having a motion incident to a weft replenishing operation of the loom, an actuator element on the operating member, a thread remover member movable from the thread non-pick-up position to thread pick-up position, an actuated element on the remover member for cooperation with the actuator element, a shuttle position detector normally in non-detecting position but moving to detecting position incident to a weft replenishing operation, means mounting one of said elements on the corresponding member for movement relative to the other element, and control mechanism for said one element controlled by said shuttle position detector effective upon movement of the shuttle feeler to shuttle detecting position to establish cooperative relation between the elements and effective incident to movement of the shuttle feeler away from the detecting position thereof by a misplaced shuttle prior to said motion of the operating member to move said one element out of cooperative relation with respect to the other element to prevent the operating member from moving the remover member.

3. In a weft replenishing loom, an operating member having a motion incident to a weft replenishing operation of the loom, an actuator element on the operating member, a thread remover member movable from thread non-pick-up position to thread pick-up position, an actuated element on the remover member for cooperation with the actuator element, a shuttle position detector normally in non-detecting position but moving to detecting position incident to a weft replenishing operation, means mounting one of said elements on the corresponding member for movement relative to the other element, and control mechanism for said one element controlled by said shuttle position detector effective upon movement of the shuttle feeler to shuttle detecting position to establish cooperative relation between the elements and effective incident to movement of the shuttle feeler away from the detecting position thereof by a misplaced shuttle prior to said motion of the operating member to exert a positive force on said one element to move the latter out of cooperative relation with respect to the other element to prevent the operating member from moving the remover member.

4. In a weft replenishing loom, a bobbin transerrer member having an operating stroke on a weft replenishing operation of the loom, a thread remover member normally in thread non-pick-up position but movable to thread pick-up position, two cooperative elements, one on each of said members, one of said elements being movable with respect to the member corresponding thereto and the other element, a shuttle position detector moving from normal position to detecting position incident to a weft replenishing operation of the loom, control means for said one element operatively connected to the shuttle position detector, and resilient means moving said one element into cooperative relation with respect to the other element when the shuttle position detector moves to detecting position, said control means exerting a positive force moving said one element to non-cooperative position with respect to the other element in the event that the shuttle position detector is moved by a misplaced shuttle to prevent movement of the remover member to the pick-up position thereof by a transerrer member.

5. In a weft replenishing loom, a transerrer arm having an operative stroke on a weft replen-

ishing beat of the loom, an actuator element supported by and movable with respect to the transfer arm, a thread remover normally in thread non-pick-up position but movable to thread pick-up position, an actuated element on the thread remover, said elements being in cooperative relation preparatory to a weft replenishing operation of the loom in position to transmit force from the transfer arm to the thread remover to move the latter to thread pick-up position when the transfer arm has said operative stroke, a shuttle position detector, and mechanism connected to the shuttle position detector controlling the actuator element and moving the latter element out of cooperative position with respect to the actuated element in the event that the shuttle position detector is moved by a misplaced shuttle to prevent the transfer arm from moving the thread remover to pick-up position.

6. In a weft replenishing loom, a transfer arm having an operative stroke on a weft replenishing operation of the loom, an actuator element pivoted on the transfer arm, a thread remover normally in thread non-pick-up position but movable to thread pick-up position, an element on the remover for cooperation with the actuator element, said elements being in cooperative position preparatory to a weft replenishing operation of the loom to transmit force from the transfer arm to the remover to move the latter to pick-up position when the transfer arm has an operative stroke, and shuttle feeler mechanism controlling the actuator element and effective to move the latter element out of cooperative position with respect to the element on the remover when the shuttle feeler mechanism is moved by a misplaced shuttle to prevent the transfer arm from moving the thread remover to pick-up position.

7. In a weft replenishing loom, weft replenishing mechanism including a transfer arm having an operating stroke on a weft replenishing beat of the loom, an actuator element pivoted on the transfer arm, a thread remover movable from thread non-pick-up to pick-up position, an element on the remover positioned for cooperation with the actuator element incident to a weft replenishing operation, a lever pivoted on the replenishing mechanism controlling the position of the actuator element, and shuttle feeler mechanism operatively connected to said lever and effective in the event that the shuttle feeler mechanism is moved by a misplaced shuttle to cause said lever to move the actuator element out of operative position with respect to the element on the remover member.

8. In a weft replenishing loom, an operating member having an operating stroke on the weft replenishing beat of the loom, a thread remover member normally in thread non-pick-up position but movable to thread pick-up position, an actuator element on the operating member, an actuated element on the remover member, one of said elements being movable with respect to

the associated member, said elements being in cooperative position incident to a weft replenishing operation, a lever controlling the position of said one element, and a shuttle position feeler operatively connected to the lever and effective when moved by a misplaced shuttle to cause said lever to move said one element out of operative position with respect to the other element to prevent movement of the remover member by the operating member.

9. In a weft replenishing loom, a bobbin transfer member having an operating stroke on a weft replenishing beat of the loom, an actuator element supported by and movably mounted on the transfer member, means tending normally to move said element to operating position, a thread remover member positioned for movement to thread pick-up position by said actuator element when the latter is in the operating position thereof on an operating stroke of the transfer member, and shuttle feeler mechanism controlling said actuator element holding the latter in inoperative position when the feeler is in the normal position thereof, said feeler moving to the detecting position thereof preparatory to a replenishing operation and said means thereupon moving the element to the operative position thereof, said shuttle feeler mechanism if moved by a misplaced shuttle being effective to move said actuator element away from the operative position thereof to prevent movement of the remover member to the pick-up position thereof by the transfer member.

10. In a weft replenishing loom, a bobbin transfer member having an operating stroke on a weft replenishing operation of the loom, a thread remover member normally in thread non-pick-up position but movable to thread pick-up position, two cooperative elements, one on each of said members, one of said elements being movable relatively to the member corresponding thereto, said elements being in cooperative relation with respect to each other preparatory to a weft replenishing operation of the loom and effective when in said cooperative relation to cause the transfer member to move the remover member to thread pick-up position during an operating stroke of the transfer member, and a shuttle position detector operatively related to said one element and effective when engaged by a misplaced shuttle to move said one element out of cooperative relation with respect to the other element to prevent the transfer member from moving the remover member to pick-up position.
